(57) **CLAIM**

The ornamental design for a vertical spray actuator, as shown and described.

DESCRIPTION

FIG. 1 is a perspective view as seen from the top, front and right side of a vertical spray actuator showing our new design;

FIG. 2 is a front elevational view thereof;

FIG. 3 is a right side elevational view thereof, the left side elevation being a mirror image thereof;

FIG. 4 is a rear elevational view thereof; and,

FIG. 5 is a top plan view thereof.
